(57) **CLAIM**

The ornamental design for a tower merchandiser, as shown and described.

DESCRIPTION

FIG. 1 is a perspective view of the tower merchandiser, in accordance with the design;

FIG. 2 is a front view of the tower merchandiser of FIG. 1;
FIG. 3 is a rear view of the tower merchandiser of FIG. 1;
FIG. 4 is a right side view of the tower merchandiser of FIG. 1; and,

FIG. 5 is a top plan view of the tower merchandiser of FIG. 1.

The broken lines depict portions of the article that form no part of the claimed design.

1 Claim, 5 Drawing Sheets
